UNITED STATES PATENT OFFICE.

AUGUST BECK, OF NEW YORK, N. Y.

DESIGN FOR A QUILTED LINING.

SPECIFICATION forming part of Design No. 14,237, dated August 2nd, 1883.

Application filed July 21, 1883. Term of patent 3½ years.

To all whom it may concern:

Be it known that I, AUGUST BECK, of the city, county, and State of New York, have invented a new and original Design for Quilted Lining, of which the following is a full, clear, and exact description, reference being had to the accompanying drawing, making part of this specification, which represents the nature of my design.

The object of this invention is to furnish a novel design for quilted lining; and it consists of a quilted lining stitched in figures having a V-shaped point, parallel sides, and lateral end, that form the connection with the next figure.

A in the drawing represents a quilted lining in which the quilting is produced by a number of parallel lines of stitches, B, that form pointed figures, each of which is composed of a V-shaped point, a, parallel sides b b, and

lateral inclined ends d d. The figures formed by the parallel lines of stitches produce continuous panels or moldings between said lines, that impart an ornamental character to the quilting.

Having thus described my invention, I claim as new and desire to secure by Letters Patent—

A design for quilted lining, composed of a series of pointed figures on the lining, each figure having a V-shaped point, parallel sides, and laterally-inclined ends, substantially as shown and described.

In testimony that I claim the foregoing as my invention I have signed it this 15th day of May, 1883.

AUGUST BECK.
